UNITED STATES PATENT OFFICE

132,250

DESIGN FOR A BUILT-IN TUMBLER HOLDER

Henry Dreyfuss, New York, N. Y., assignor to Crane Co., Chicago, Ill., a corporation of Illinois

Application November 6, 1941, Serial No. 104,057

Term of patent 14 years

To all whom it may concern:

Be it known that I, Henry Dreyfuss, a citizen of the United States, residing at New York, in the county of New York and State of New York, have invented a new, original, and ornamental Design for a Built-In Tumbler Holder, of which the following is a specification, reference being had to the accompanying drawing, forming part thereof.

Fig. 1 is a plan view of the holder embodying my design.

Fig. 2 is a front view thereof.

Fig. 3 is a side view thereof.

I claim:

The ornamental design for a built-in tumbler holder, substantially as shown.

HENRY DREYFUSS.
